Inventor:

Stephen W. Rathbun,
by J. W. St. John,
Atty.

UNITED STATES PATENT OFFICE.

STEPHEN W. RATHBUN, OF MARION, IOWA.

PRINTER'S STAND.

SPECIFICATION forming part of Letters Patent No. 408,747, dated August 13, 1889.

Application filed August 13, 1888. Serial No. 282,682. (No model.)

To all whom it may concern:

Be it known that I, STEPHEN W. RATHBUN, a citizen of the United States, residing at Marion, in the county of Linn and State of Iowa, have invented certain new and useful 5 Improvements in Printers' Stands; and I do hereby declare the following to be a full, clear, and exact description of the invention, such as will enable others skilled in the art to which it appertains to make and use the same.

The object of my invention is to produce a printer's cabinet capable of being folded together to economize space and for the better protection of the type and cases.

15 The invention consists in the construction, combination, and arrangement of parts, as fully hereinafter set forth and claimed.

In the accompanying drawings, forming a part of this specification, Figure 1 is a front 20 view, in perspective, of a single stand or cabinet embodying my invention; Fig. 2, a rear view, in perspective, of the same; Fig. 3, a front view, in perspective, of a double stand capable of being closed together to practically 25 the same dimensions as the single one.

Similar letters of reference indicate corresponding parts.

Referring to the drawings, A is the body of the cabinet, which is in the general form, for 30 the most part, of the cabinets in common use, consisting of a frame-work with ends and back, as shown, and cleats inside each end to support the type-cases.

The back may be dispensed with, if desired, 35 to admit of cases being drawn out from that side, but in practice I prefer to inclose the cabinet on this side for the better protection of the contents of the cases against dust and dirt.

40 The upper portion of the stand is made to incline, as shown, to secure the proper angle of the type-case H resting thereon, the case itself resting upon the end pieces A'', and the case is secured from slipping down by the 45 upward projection of the front piece A', while the similar projection of the lower uprights A''' A''' secure it from displacement endwise. The upper case is supported on two arms B B, hinged to the back of the stand by 50 two double-jointed hinges a a. The lower ends of these arms, when in position to support the case, rest upon the upper face of

rearwardly-extending blocks C C. The middle portion of the hinges corresponds in length to the thickness of the type-case, so that when 55 the arms are folded down they rest upon the top of the lower case, as shown in Fig. 2. A board D, connected with these arms, aids in supporting the case, and when folded down, as in Fig. 2, completely covers the case, protecting it from dirt and otherwise. By this arrangement the stand is made capable of containing a number of cases of type thoroughly protected when not in use, and, as will be seen, the construction is such that the lower 65 case may be covered without removing from its normal position.

The stand may be of any desirable length—double, threefold, or otherwise—by simple extension of the frame corresponding to the 70 design shown in Figs. 1 and 2. For the sake of economizing space, however, and for convenience in handling, clearing the floor, &c., I prefer to make the double stand as indicated in Fig. 3. In this case the main portion 75 corresponds for the most part to the single stand already described. It is provided with a supplemental extension E, adjustably connected with the main stand by bars E' E'' and F F near the top and bottom, respectively. These bars extend through the end of the stand A'', suitable mortises b b' being provided therein for that purpose.

The lower bars F F may be supported upon and guided by a rail G, secured to the lower 80 part of the cabinet, as shown. To provide for the easy movement in opening and closing the supplemental stand, it may be furnished with casters d d. The outer end of this supplemental stand is provided with a 90 single hinged arm B, as already described.

In Fig. 3 the stand is represented as about half closed together, the further closing thereof being done simply by pushing it inwardly. When drawn out to its extreme position, the upper part of the supplemental stand is swung forward slightly, so that the gains c c at the ends of the front boards A' and E' match together, and the two parts are then flush with each other their entire length. 95 Provision is made for this slight shifting of the supplemental stand by correspondingly widening the mortises b b', as indicated in Fig. 4. When in its normal position, the sup-

plemental stand supports the outer ends of the upper and lower type-cases, the inner ends thereof resting upon the other stand, which should project beyond the cases resting thereon sufficiently for that purpose. As is indicated in Fig. 3, the cases when in position in the cabinet are so disposed as to practically exclude dirt and to prevent mixing of type by meddlesome hands and the like.

10 Thus constructed the cabinet secures a convenient disposition of the type-cases and protection of their contents, and when not in use may be closed into a small compass for economy of space, as before referred to.

15 Having thus described my invention, what I claim as new, and desire to secure by Letters Patent, is—

1. In a printer's stand, the combination of the body A, having a front upper piece A' 20 and the ends A'' A'', inclined at the top, said front piece extending slightly above said inclination, whereby the lower case is unsupported, and the arms B B hinged to said stand and adapted to support the upper case, substantially as and for the purpose set forth.

2. The combination, in a printer's stand, of the stand A A' A'', adapted to support the lower case, the arms B B, connected board D, supporting blocks C C, and double-jointed 30 hinges a a, substantially as and for the purpose set forth.

3. In a printer's stand, the combination, with the stand, substantially as described—that is to say, having a support for the lower case and the hinged support for the upper one adapted to fold downward when not in use—of the supplemental stand connected to said main stand by telescoping arms, and having a hinged support for the upper case, substantially as described, whereby said supplemental stand is adapted to be closed against the main stand, or drawn outward to form a double stand, as specified.

4. In a printer's stand, the combination of a main stand, substantially as described, having supports for upper and lower type-cases, the mortises b b', adapted to allow limited backward and forward movement of bars E' E'', and supplemental stand E, having connected bars E' E'' and F F, extending through 50 mortises in the main stand, the forward bar E' having a gain c, matching a similar gain in the board A' of the main stand, all substantially as and for the purpose set forth.

In testimony whereof I affix my signature 55 in presence of two witnesses.

STEPHEN W. RATHBUN.
